(57) **CLAIM**

The ornamental design for a hearing aid with module, as shown and described.

DESCRIPTION

FIG. 1 is a perspective view of a hearing aid, showing our new design with the module detached;

FIG. 2 is a bottom plan view thereof;

FIG. 3 is a front elevational view thereof;

FIG. 4 is a rear elevational view thereof;

FIG. 5 is a left side elevational view thereof, the right side being a mirror image;

FIG. 6 is an exploded view with a module in unattached position;

FIG. 7 is a perspective view with the module in attached position;

FIG. 8 is an exploded view with two modules in unattached position; and,

FIG. 9 is a perspective view with the two modules in attached position.
